CLASS "B" AUDIO AMPLIFIER

Loy E. Barton, Collingswood, N. J., assignor to
 Radio Corporation of America, a corporation of
 Delaware

Application December 29, 1933, Serial No. 704,509

12 Claims. (Cl. 179—171)

The present invention relates to electric discharge amplifiers and more particularly to audio-frequency power or output amplifiers of the class "B" type.

5 In an audio-frequency power amplifier of the above type, a pair of electric discharge devices or tubes are disposed in balanced or push-pull relation and are operated at substantially anode current cut-off. There are, however, further distinguishing features of an amplifier of this type.

10 More particularly an amplifier of the above type may be defined as a modified class "B" amplifier, or as a class "B" audio-frequency amplifier, as distinguished from a normal single ended class "B" amplifier employed in a tuned plate circuit radio-frequency amplifier system, and having a power output proportional to the square of the excitation or input grid voltage. The two types of amplifiers are similar only in 20 that both employ tubes biased substantially to anode current cut-off and that the anode current increases in response to applied signal voltages.

25 The modified class "B" amplifier or class "B" audio-frequency amplifier is further characterized by the fact that the tubes are arranged in push-pull or balanced relation, so that each functions during approximately one half of each signal voltage wave or cycle. The tubes are 30 further provided with balanced input and output circuits each having an operating impedance substantially lower than the minimum input and output operating impedances of the tubes, whereby the tubes may be driven by the signal potentials far into the positive grid bias range of 35 operation and may draw increasing grid and plate current to the limit of the space charge or emission for maximum power output.

40 A varying load is therefore placed upon the driving amplifier or stage for a class "B" audio-frequency amplifier and both the grid current and the plate current vary through wide ranges. High transient voltages may also be caused by 45 steep signal wave fronts occurring in the plate circuit of a class "B" audio-frequency amplifier, because the normally low impedance load above mentioned may become ineffective in response to the high frequency transient signal waves.

50 It has been found that the leakage reactance of the output transformer for the class "B" power amplifier in combination with the effective output circuit capacity across the primary or plate windings is responsive to the high frequency oscillations set up by the transient signal voltages 55 and may often cause the output transformer of

a class "B" audio-frequency amplifier to break down or arc over. Appreciable distortion may occur even though the transformer does not arc or break down.

Accordingly, it is an object of the present invention to provide an improved class "B" audio-frequency amplifier which is not subject to arc over or break down in the output transformer in response to signal waves causing high transient voltages, and which is capable of handling a 10 greater power output without distortion of the signal wave. 5

It is a further object of the present invention to provide an improved class "B" audio-frequency amplifier having an improved operating characteristic in response to signals having a high 15 amplitude and a relatively wide audio-frequency range.

It is a still further object of the present invention to provide a balanced electric discharge 20 amplifier of the class "B" audio-frequency type, having a balanced output circuit, for suppressing high frequency oscillations which normally tend to produce break down voltages in the output transformer. 25

It is also a still further object of the invention to provide an improved balanced output circuit for a class "B" audio-frequency amplifier.

The invention and the above and further objects thereof will be better understood from the 30 following description, when taken in connection with the accompanying drawing, and the scope of the invention will be pointed out in the appended claims.

35 In the drawing, Fig. 1 is a schematic circuit diagram of a class "B" audio-frequency power or output amplifier embodying the invention, and Fig. 2 is a curve diagram and amplifier circuit illustrating certain operating characteristics of the amplifier circuit shown. 40

Referring to Fig. 1, 5 and 6 are electric discharge amplifier devices or tubes suitable for class "B" audio-frequency amplifiers. In the present example, each tube is provided with a cathode 7, an anode 8, and two spaced grid electrodes 9 and 10 located between the cathode and the anode. These tubes are of the type known commercially as the RCA-46 Radiotron. 45

The grid electrodes 9 and 10 are connected in parallel to form, in effect, one grid or control 50 electrode in each tube. The parallel grid electrodes are then connected to the opposite ends of a balanced input circuit 11, provided in connection with a center tapped secondary 12 of a balanced signal input transformer 13. The 55

primary 14 of the input transformer is connected with suitable signal input terminals indicated at 15 which terminals may be connected with any suitable source of audio-frequency signals (not shown) capable of driving the grids 9-10 to the limits of the positive operating range.

Under such conditions of operation, the grids may draw a relatively high current and, accordingly, the input circuit must be capable of supplying audio-frequency power without signal wave distortions. For this reason, the impedance of the secondary 12 is relatively low with respect to the impedance between the grids and cathodes of each tube when driven to the limit of the positive grid bias range.

It will be noted that the center tapped secondary 12 is provided with a return lead 16 directly to the suitably center tapped cathode. A pair of terminals 17 in the lead 16 are provided for introducing a biasing potential if desired. With the present arrangement, the grids 9 may receive the proper biasing potential for essentially zero plate current with no signal. In this case, a double grid control is used whereby two spaced grid electrodes are connected in parallel, as one, between the cathode and the anode of each tube, and the normal anode current is reduced substantially to zero, without signal, for zero bias.

A class "B" audio-frequency amplifier of the biased type is shown and described in my copending application, Serial No. 586,874, filed January 15, 1932, and a class "B" audio-frequency amplifier of the zero biased type is shown and described in my copending application, Serial No. 589,847, filed January 30, 1932, both applications being assigned to the same assignee as this application.

The electric discharge amplifier devices 5 and 6 are further provided with a balanced output circuit 18 and an output transformer 19 having a balanced primary winding 20, provided with a center tap connection 21 with a supply lead 22 from a suitable well regulated source of plate potential indicated at 23. The negative end of the plate supply means is connected through a cathode return lead 24 to the lead 16, whereby the plate potential is applied between the cathodes and the anodes of the devices 5 and 6 through the balanced primary winding 20 and the output circuit 18 connected with the outer terminals of the balanced primary winding 20.

The output transformer 19 has a ratio such that the load, indicated at 26 in connection with the secondary 27, reflected over into the primary side of the transformer or into the anode output circuit, is of a relatively low impedance as compared with the lowest operating output impedance of either of the devices 5 and 6, whereby wide changes in the anode output current in response to signals, as in the case of the grids being driven to a maximum positive limit, may not cause appreciable signal potential drop and distortion in the output circuit.

The operation of the circuits shown is such that each amplifier device operates alternately on the positive half of each signal wave. The negative half of each signal wave is not effective to operate the amplifier, since the devices 5 and 6 are normally substantially at anode current cut-off.

In response to signals of high amplitude, the grid and anode currents may rise to relatively high values as will be seen from a consideration of curves given in the diagram of Fig. 2, to which attention is now directed. In the diagram, the curves 28 and 29 are anode current curves and

the curves 30 and 31 are grid current curves for normal and transient voltage operation respectively of the amplifier in Fig. 1, provided with bias potential at the terminals 17. Each of the curves is plotted with respect to grid voltage along the horizontal axis and current along the vertical axis.

These curves are plotted for electric discharge amplifier devices known commercially as RCA UV-849 for a high power audio-frequency amplifier and with grid bias.

It will be noted that the anode current may rise from substantially zero to over 1100 milli-amperes while the grid current varies from zero to over 100 milli-amperes, indicating the wide range of variation of current in both the input and output circuits of the class "B" amplifier.

In response to audio-frequency signals, having wide frequency range and high amplitude, abrupt changes may occur which cause high transient voltages to be developed in the output circuit, sufficient to burn out or arc over the output transformer 19 as will be seen from an inspection of the curves given in Fig. 2, and for the reason that the output transformer has an appreciable leakage reactance which tunes with effective circuit capacity across the primary 20, to respond to or resonate at relatively high oscillation frequencies. High transient voltages having steep wave fronts are prevented from being transmitted from the load circuit by the tuned circuit comprising the transformer leakage reactance and the effective circuit capacity in series, as indicated diagrammatically in dotted lines on the output circuit 18 at 32 and 33 respectively in Fig. 1. 35

The effective capacity across the primary winding in the anode circuit is constituted principally by the distributed capacity of the transformer winding and the external circuit capacity which is chiefly the plate or anode to ground capacity, the effective value of which may be higher than the static capacity when the circuit is in operation.

It has been found that the oscillations at the resonant frequency of the leakage reactance and its combining circuit capacity may effectively be reduced by damping and by-pass means in the output circuit, whereby the transient voltages are reduced to safe values to prevent transformer break-down and to reduce distortion of the output wave.

The distortion may vary in different amplifiers depending upon the type of amplifier devices used and the power to be transmitted thereby. The effect of such distortion will be noted particularly in the shape of the curves 28 and 29 at the upper end as indicated at 34 and on the curve 31 at 35.

It has been found that the oscillations at the resonant frequency of the leakage reactance of the output transformer and the effective circuit capacity in series therewith, may be damped to effectively reduce the transient voltages by means of an impedance located adjacent to each anode in the balanced output circuit, as indicated at 36, and a relatively small capacity 37 between each anode and the center tap 21 of the output transformer, thereby to make the impedance 36 effective in each half of the output circuit at certain lower frequencies. This capacity is effectively in series with the leakage reactance and circuit capacity and in parallel across the output device between the anode and the cathode. A closed circuit is thus formed with each half of the output circuit comprising an impedance, the output circuit capacity and an additional capacity all in 70 75

series with the output transformer leakage reactance.

The impedance 36 is preferably a non-inductive resistor having a relatively low resistance value compared with that of the load in the output or anode circuit. In the present example, with a load impedance of 2500 ohms, the impedance 36 may be a resistor having a value of approximately 75 ohms and the capacitor at 37 may be a small 10 condenser having a capacity value of substantially 75 micro-micro-farads. Ordinarily, the resistance inserted in series with the plate or anode in each half of the balanced output circuit is less than 5 to 10% of the load impedance in each half 15 of the output circuit.

The capacity 37 effective in parallel with each amplifier device should be sufficiently large to permit appreciable currents at the lowest oscillation frequency to be transmitted through it, thereby to cause the impedance or resistance in 20 series with the anode to be effective in damping the oscillations at the resonant frequency of the leakage reactance and the effective circuit capacity.

It will be noted that the condensers 37 are connected between points in the output circuit across which exists a relatively low direct current potential difference. The connection, as shown, is between each anode and the center tap of the 30 output transformer, whereby the potential existing across the condenser in each half of the output circuit is only that resulting from the potential drop through each half of the transformer primary winding and the still lower potential drop through each of the impedances 36.

It will be seen therefore that the condensers 37 may be of relatively low cost for the reason that ordinarily they need be insulated only for low direct current potentials, as compared with potentials of the plate supply, which may be in the order of several hundred volts, although the condenser is effectively connected between the anode and the cathode of each amplifier device. However, the alternating current potential or audio 40 frequency voltage across the condensers may be high. In the present example, the condensers have the full alternating current or audio frequency voltage which is 2500 volts in this case and when the condensers are effective in suppressing 50 oscillations they must pass appreciable current at frequencies above the audio frequency band. However, in general, the condensers are of relatively low cost because of the small capacity required.

It will be seen that each half of the output circuit is in itself, a closed oscillatory circuit provided with individual damping means of relatively low impedance. In a class "B" audio-frequency amplifier, the entire output circuit must be of relatively low impedance compared with that of the amplifier devices and it will further be seen that the relative impedances of the devices 36 and the output circuit are such that the additional resistance in circuit may not appreciably affect the 60 shape of the signal wave or the power output of the amplifier. In the example given, the additional 75 ohms in circuit with 2500 ohms does not materially increase the voltage distortion in the circuit. Furthermore, because of its uniform frequency characteristic, non-inductive resistors are 65 preferable as the impedance devices.

By utilizing a circuit in accordance with the invention, all of the advantages of the efficient maximum power handling ability and substantially distortionless operation of a class "B"

audio-frequency amplifier may be realized without signal distortion and without subjecting the output transformer to damage by arcing over or burning out.

It is desirable ordinarily that a wide range of 5 audio frequency signals may be transmitted by an amplifier and it is possible in the class "B" amplifier of the present example to a greater extent, without distortion, than has heretofore been possible, particularly with high signal amplitudes. 10

It is common knowledge that in general an audio-frequency transformer such as the transformer 19, designed to transmit audio-frequency signals from 30 to 15,000 cycles has comparatively 15 high leakage impedance to signals in the frequency range of 20,000 cycles and higher. The fact that leakage impedance is present due to leakage inductance and is relatively large at high frequencies makes it obvious that the primary circuit cannot effectively be loaded by the secondary. Therefore, the primary load becomes essentially an inductance 32 and capacity 33 in series and have a resonant period which in general occurs at frequencies above the audio frequency range. It will be seen that since little effective 25 resistance is present to prevent high currents through 32 and 33 the voltage across these impedances may become relatively high if the circuit is excited at its resonant frequency. The sharp bend of the curves 29 and 28 at the upper end due 30 to over excitation of the grid and the abrupt rise of the grid current at about the same time introduce harmonics in the plate circuit. The negative bend of the grid current curves also cause abrupt changes in the plate current curve. These 35 abrupt changes for low frequencies, say 200 cycles, may result in harmonics well within the audio range but at higher frequencies, for example 5000 cycles, or even down to low frequencies, if the plate current changes are sufficiently abrupt the 40 harmonics introduced may easily fall within the resonant frequency range of the above mentioned impedances, in which case high voltage transients appear and with the transients or damped oscillations increased distortion results. 45

Since the high voltage actually appears across the terminals of the transformer primary, a capacity across the primary such as the effective plate capacity and additional capacity 37 changes 50 the resonant frequency but has little effect upon its amplitude unless the frequency is changed into the region in which the secondary load would be effective on the primary. However, if a resistance of comparatively low value is added as at 38 55 the loading at the resonant frequency of the system easily suppresses the high frequency resonant voltages.

I claim as my invention:

1. In a class "B" audio-frequency amplifier, the 60 combination of an output transformer having a primary winding provided with a center tap connection, a pair of electric discharge amplifier devices having an anode output circuit connected in balanced relation to said primary winding, said 65 transformer providing an output load impedance lower than the normal output operating impedance of said devices and having leakage reactance and distributed capacity responsive to high frequency oscillations, means providing a series impedance of relatively low ohmic resistance in each half of said balanced output circuit and means providing a shunt capacity across each half of said output circuit in series with said leakage reactance. 70 75

2. In a class "B" audio-frequency amplifier, the combination of an output transformer having a primary winding provided with a center tap connection, a pair of electric discharge amplifier devices having an anode output circuit connected in balanced relation to said primary winding, said transformer providing an output load impedance lower than the normal output operating impedance of said devices and having leakage reactance and distributed capacity responsive to high frequency oscillations, and means for damping said high frequency oscillations comprising a series impedance device of relatively low ohmic resistance in said output circuit adjacent to each anode, and a by-pass capacitor connected between the anode end of each of said impedance devices and the center tap of said primary winding.
3. In a class "B" audio-frequency amplifier, the combination with a pair of balanced electric discharge amplifier devices, of a balanced output circuit therefor comprising an output transformer having a center tapped primary winding and having a predetermined leakage reactance and distributed capacitance, an impedance device of low ohmic resistance connected in said output circuit adjacent to each of said amplifier devices, and a by-pass condenser connected between the center tap of the transformer winding and each of said impedance devices to complete a damped oscillatory circuit through each of said devices and one half of said transformer winding.
4. In a class "B" audio-frequency amplifier, the combination with an output anode circuit therefor and an output transformer in said circuit, of means for damping high frequency oscillations in said circuit comprising a resistor in each half of the balanced output circuit having a resistance value in ohms substantially lower than the ohmic impedance of the output circuit, and means providing an effective anode to cathode capacity across said output circuit to resonate the leakage reactance in said circuit at a frequency above the effective audio frequency range of said amplifier.
5. In an audio-frequency amplifier, the combination with a pair of electric discharge amplifier devices having a balanced output anode circuit, of an output transformer in said circuit providing a load therein of relatively low impedance with respect to the output impedance of said devices, and an impedance device in each half of said balanced output circuit adjacent to the output anode of each of said devices, having an ohmic resistance less than 10% of the impedance of said output circuit in series therewith.
6. In an audio-frequency power amplifier having low impedance balanced input and output circuits for a pair of electric discharge power amplifier devices, of means for damping oscillations at the resonant frequency of the leakage reactance and effective capacitance in the output circuit thereby to reduce transient voltages across said output circuit to desired operating values, said means comprising an impedance device in said output circuit adjacent to each of said amplifier devices of an impedance value less than 10% of the load impedance of said output circuit.
7. In an audio-frequency power amplifier having low impedance balanced input and output circuits for a pair of electric discharge power amplifier devices, of means for damping oscillations at the resonant frequency of the leakage reactance and effective capacitance in the output

circuit thereby to reduce transient voltages across said output circuit to desired operating values, said means comprising an impedance device in said output circuit adjacent to each of said amplifier devices of an impedance value less than 10% of the load impedance of said output circuit, and by-pass capacitors across said circuit effectively in parallel with the anode to cathode impedance of said devices and having lower impedance to superaudible transient currents than the remainder of said circuit through said leakage reactance.

8. An audio-frequency amplifier including in combination, a pair of electric discharge devices each having an anode, a cathode, and a control grid, said devices being connected in balanced relation to each other and being adapted to be biased substantially to anode current cut off, an input circuit of low impedance with respect to the grid impedance of each of said devices when drawing a predetermined maximum grid current, an output circuit of low impedance with respect to the anode impedance of each of said devices, and a resistor connected electrically directly with each anode in series with the output circuit, said resistors each providing an impedance substantially lower than that of said output circuit.

9. An audio-frequency amplifier including, in combination, a pair of electric discharge devices each having an anode, a cathode, and a control grid, said devices being connected in balanced relation to each other and being adapted to be biased substantially to anode current cut off, an input circuit of low impedance with respect to the grid impedance of each of said devices when drawing a predetermined maximum grid current, an output circuit of low impedance with respect to the anode impedance of each of said devices, and a resistor connected electrically directly with each anode in the output circuit, said resistors each having an impedance substantially lower than that of said output circuit and means connected to said output circuit for effectively increasing the anode to cathode capacity of said circuit.

10. A class "B" audio-frequency amplifier including a pair of balanced electric discharge devices each having a cathode, an anode, and a control grid structure connected with the cathode and so spaced between the cathode and anode thereof that said devices operate at substantially zero normal anode current and bias potential, a balanced output circuit connected between said anodes and including a balanced output transformer having a center tapped primary winding in said circuit, a resistor connected between each anode and said primary winding and a by-pass condenser connected between each anode and the center tap of said primary winding, said resistor being less than 10% of the impedance of the output circuit.

11. In an audio-frequency amplifier, the combination with a pair of electric discharge amplifier devices having a balanced output anode circuit, of an output transformer in said circuit providing a load therein of relatively low impedance with respect to the output impedance of said devices, and said transformer having a leakage reactance and an effective capacity across the primary winding thereof whereby it is responsive to high frequency oscillations set up by transient signal voltages and an impedance device in each half of said balance output circuit adjacent to the output anode of each of said devices having a resistance value in ohms substantially lower

than the ohmic impedance of the output circuit.

12. In a class "B" audio-frequency amplifier, the combination with an output anode circuit therefor and an output transformer in said circuit, of means for damping high frequency oscillations in said circuit comprising a resistor in each half of the balanced output circuit having

a resistance value in ohms substantially lower than the ohmic impedance of the output circuit, and a capacity connected between each anode end of said output anode circuit and a center tap on the primary of said output transformer. 5
